UNITED STATES PATENT OFFICE.

OTIS E. MCCOY, OF BALTIMORE, MARYLAND.

SWITCH.

1,137,875.

Specification of Letters Patent. Patented May 4, 1915.

Application filed April 13, 1912. Serial No. 690,609.

To all whom it may concern:

Be it known that I, OTIS E. MCCOY, a citizen of the United States of America, residing at Baltimore, in the State of Maryland, have invented new and useful Improvements in Switches, of which the following is a specification.

This invention relates to improvements in switches for opening and closing electric circuits and has particular application to a switch for use in conjunction with the instruments of wireless systems.

In carrying out the present invention, it is my purpose to provide a switch of this type whereby the sending and receiving instruments may be connected to and disconnected from the aerial at will, according to which instrument it is desired to utilize.

Furthermore, I aim to provide a switch which shall include a horizontal base board carrying the terminal contacts of the circuits and having pivotally mounted thereon a plurality of switch blades adapted to engage the terminal contacts to close such circuits, each blade consisting of relatively angular arms and movable in a plane parallel to that of the base board so that when one of the instruments is connected in its respective circuit, the other instrument will be cut out of its circuit.

Another purpose of my invention is the provision of a switch which shall include a base board carrying terminal contacts, and switch blades pivotally mounted upon the base board and movable in a plane parallel with that of such board, the pivoted portion of each blade being split and having an aperture contiguous the split portion to receive the pivot, pin or screw so that subsequent to the application of the blade to the pivot screw, the arms thereof may be bent angularly relatively to each other and locked to the pivot, the walls of the split portion serving to lock the blade in its applied position.

My invention also involves the provision of a switch and a novel form of terminal contact therefor, such contact being stamped from a single sheet of metal and formed to provide a contact for the switch blade and a terminal receiving member for the conductor of the electric current.

With the above and other objects in view, the invention consist in the construction, combination and arrangement of parts here-

inafter set forth in and falling within the scope of the appended claims.

In the accompanying drawing; Figure 1 is a top plan view of a single pole double throw switch to be hereinafter disclosed. Fig. 2 is a central longitudinal sectional view of the same. Fig. 3 is a detail view of a contact, parts being in section and other parts in elevation. Fig. 4 is a fragmentary plan view of a modified form of switch blade. Fig. 5 is a detail sectional view on the line 5—5 of Fig. 1.

Similar reference characters designate like parts throughout the several views.

Referring now to the accompanying drawing in detail, my improved switch, as shown, embraces a base board 1 of substantially rectangular outline and constructed of suitable insulating material.

Mounted upon the base board 1 and secured thereto adjacent the opposite side edges thereof are pairs of coöperating contacts 2, 2, 3, 3, and 4, 4 spaced suitable distances apart and adapted to facilitate the closing of the circuits to the respective instruments of the system in which the switch is installed.

Each contact of the pairs 2, 3 and 4, comprises a single strip of metal, as shown in Fig. 3, bent upon itself intermediate its ends as at 5 to form arms 6 and 7. The arm 7 is bent intermediate its length to form a substantially curved portion 8 and has its free extremity 9 arranged parallel with the main body portion of the arm 7 and spaced therefrom to provide a switch blade receiving contact, the blade being adapted to enter the space between the arm 7 and its free extremity 9 to close the circuit. The arm 6 is bifurcated to provide spaced parallel limbs 10, 10 converging toward each other at their free ends as at 11, 11 and the portion of the material between the limbs 10, 10 is bent downwardly as at 12 thence upwardly as at 13 to provide a spring tongue 100 and coöperating with the limbs 10, 10 to hold the terminal *a* of a conductor, the clamping action produced between the tongue 12 and limbs 10, 10 serving to securely hold the conductor terminal to the contact.

The upwardly extending portion of the spring tongue 13 terminates in a manipulating finger 14 adapted to be depressed by the thumb of an operator, the forefinger of such

operator being held against the under surface of the converging extremities 11, 11 of the limbs 10, 10 so that upon a pressure being exerted upon the finger 14, the spring 5 tongue will be disengaged from the wire terminal to permit the removal thereof. The arms 6 and 7 at their overlapping portions are provided with alining apertures 15 adapted to receive a screw, bolt or the like whereby the contact may be fastened to the base board.

Pivots connected to the contacts 3 between the contacts 2 and 4 and intermediate the arm 7 and its free extremity 9 of such contacts 3 are switch blades 16, 16 each of which is bent intermediate its ends to provide relatively angular arms 17 and 18 and at the juncture of such arms is provided an aperture adapted to receive a pivot pin or screw 19 passed through the contact 3. It will of course be understood that the opposite contacts of each pair have their blade receiving extremities disposed in the same direction so that in the movement of 25 the switch blades 16 the contact engaging portions thereof will enter the co-operating contacts of the respective pair.

The free extremities of the arms 18 of the blades 16 are projected beyond the contacts 30 4, 4 and are pivotally connected to a manipulating member composed of a block 20 constructed of suitable insulating material and provided with a handle 21. The block 20, at one side of its pivotal connection with each blade 16 is provided with a beveled recess 22 designed to accommodate the proximate ends of the blades in the movement of the latter to open one circuit and close the other.

40 The operation of the switch just described, may be briefly stated as follows: For the purpose of illustration, let it be assumed that one contact of the pair 3 is connected to the aerial and the opposite contact of such pair grounded. Similarly, the contacts of the pair 2 connected to the receiving instrument and contacts of the pair 4 to the transmitting instrument. Thus, in the position of the switch shown in 45 Fig. 1, a circuit is completed from the ground to the respective contact of the pair 3, the arm 18 of the adjacent switch blade, one contact of the pair 4, through the transmitting instrument, the opposite contact of the pair 4, arm 18 of the opposite blade 16, thence by way of the other contact of the pair 3 through the aerial. On the contrary, should the switch be thrown from the position shown in Fig. 1 to engage the free extremities of the arms 17 of the blades 16 50 with the contacts of the pair 2, the circuits through the contacts of the pair 4 will be broken owing to the angular position of the

arms, and the circuit completed to the receiving instrument of the system, as will be 65 obvious.

In the modified form of the switch blade disclosed in Fig. 4, each blade in this instance is formed of a single strip of metal and provided intermediate its length with a 70 split portion 23 and contiguous such split portion is formed with an aperture 24 adapted to receive the pivot pin 19. Thus, the blade may be applied to its respective pivot pin through the medium of the slot 23 and 75 upon such pin entering the opening 24, the blade is bent upon itself so that the walls of the slot 23 move toward each other to contract the split portion and thereby lock the blade to the pivot pin.

80 From the foregoing description taken in connection with the accompanying drawing, the construction and manner of employing my invention will be readily understood by those skilled in the art and therefore, a further detail description of the same is 85 thought to be unnecessary.

I claim:

1. A device of the kind described comprising a resilient sheet metal strip, said strip 90 composed of a deflected portion forming at one end a switch-receiving contact, a shank extending in an opposite direction to said deflected portion, and a central slit portion formed on said shank, said slit portion consisting of a part deflected outwardly of one side of said shank, of an integral part extending into projecting position relatively to the opposite side of said shank, and of a finger portion formed terminally upon said 100 last named projecting part.

2. A device of the kind described comprising a resilient metal strip, said strip consisting of an intermediate return portion contacting its body, said body and return 105 portion having a curved-around part terminating in stem disposed parallel over said return portion, said strip also consisting of a shank extending in an opposite direction 110 relatively to said return portion, said shank consisting of two parallel limbs having terminal inturned contacting portions, of a central portion deflected outwardly of one side of said shank, of an integral part extending angularly of said deflected portion 115 and into projecting position relatively to the opposite side of said shank, and an integral finger portion formed terminally upon said projecting portion and disposed parallel to said limbs.

120 In testimony whereof I affix my signature in presence of two witnesses.

OTIS E. MCCOY.
